UNITED STATES PATENT OFFICE.

CHARLES D. RYDER, OF COVINGTON, KENTUCKY, ASSIGNOR TO THE CORCORAN-VICTOR COMPANY, OF CINCINNATI, OHIO, A CORPORATION OF OHIO.

DESIGN FOR A RIM FOR A VEHICLE-LAMP OR SIMILAR ARTICLE.

54,130.

Specification for Design.

Patented Nov. 4, 1919.

Application filed May 21, 1919. Serial No. 298,807. Term of patent 14 years.

To all whom it may concern:

Be it known that I, CHARLES D. RYDER, a citizen of the United States, and a resident of Covington, in the county of Kenton and State of Kentucky, have invented a new, original, and ornamental Design for Rims for Vehicle-Lamps or Similar Articles, of which the following is a specification, reference being had to the accompanying drawing, forming part thereof.

Figure 1 is a perspective view of the rim. Fig. 2 is a detail view in the nature of a section to show the conformation of the device at the panel portions thereof taken on the line 2, 2, of Fig. 1.

I claim:

The ornamental design for a rim for a vehicle lamp or similar article, as shown.

CHARLES D. RYDER.
